UNITED STATES PATENT OFFICE.

LEE HIRSCH, OF NEW YORK, N. Y.

DESIGN FOR A SETTING FOR PRECIOUS STONES.

56,971.

Specification for Design.

Patented Jan. 25, 1921.

Application filed July 17, 1920. Serial No. 397,129. Term of patent 14 years.

To all whom it may concern:

Be it known that I, LEE HIRSCH, a citizen of the United States, residing at New York city, borough of Manhattan, county and State of New York, have invented a new, original, and ornamental Design for a Setting for Precious Stones, of which the following is a specification, reference being had to the accompanying drawings, forming part hereof.

For convenience of illustration the invention is shown in the drawings as incorporated in a solitaire ring. Figure 1 being a top view of such a ring and Fig. 2 being a side view of such a ring, embodying the setting of the stone, which constitutes my invention.

In the drawing *a* designates the precious stone and *b* the setting therefor, which con-

sists of a plurality of concentric circular mille-grained portions which in the drawings are shown as having a slightly staggered relation with respect to each other. The setting is of whitish color like that of platinum or white gold, which when mille-grained and combined with a white stone, such as a diamond, produces the effect of a stone of considerably greater dimensions than those of the stone actually used. It is to be understood that my claim includes all substantial equivalents of my design as shown and described.

I claim:

The ornamental design for a setting for precious stones substantially as shown and described.

LEE HIRSCH.
